United States Patent Office.

W. R. SANTLEY, OF NEW LONDON, OHIO.

Letters Patent No. 94,034, dated August 24, 1869.

IMPROVED WAGON-REACH AND HOUND.

The Schedule referred to in these Letters Patent and making part of the same.

To all whom it may concern:

Be it known that I, W. R. SANTLEY, of New London, in the county of Huron, and State of Ohio, have invented a new and useful Improvement in the Construction of Wagon-Reach and Hounds; and I do hereby declare that the following is a full, clear, and exact description thereof, which will enable others skilled in the art to make and use the same, reference being had to the accompanying drawings, forming part of this specification.

This invention relates to an improvement in the construction of the reaches and hounds of wagons and carriages; and consists in making the reach and hounds of a single piece of wood, as will be hereinafter more fully described.

In the accompanying sheet of drawings—

Figure 1 represents a top view of a reach and hounds constructed according to my invention.

Figure 2 is a longitudinal view of the piece of timber or plank, prepared by sawing into the end for forming the hounds from one end, while the other end forms the reach.

Similar letters of reference indicate corresponding parts.

A is the reach.

B represents the hounds.

To make the combined reach and hounds of a single

piece, I slit the plank, as seen in fig. 2, and either place a band on, or rivet or bolt through it at the point C. The piece is then steamed and bent to the desired curve or shape on suitable moulds, and when the timber is dry the parts may be dressed as other hounds and reaches are.

Wagon-hounds are ordinarily attached to the reach by a bolt, but a stronger union is obtained by leaving the natural grain of the wood, and suitably fortifying the part, as seen at C, by a band, rivet, or bolt.

D is the axle.

E is the bolster.

This method of constructing the reach and the hounds saves considerable lumber, while the parts can be made lighter, stronger, and present a more finished and neat appearance than when made in the ordinary manner.

Having thus described my invention,

I claim as new, and desire to secure by Letters Patent—

Forming the reach and the hounds of a wagon or carriage from a single piece of wood, substantially as shown and described.

W. R. SANTLEY.
